160,720

KEY PUNCH

George H. Kress, Vestal, N. Y., and Carl W. Sundberg, Detroit, Mich., assignors to International Business Machines Corporation, New York, N. Y., a corporation of New York

Application October 5, 1949, Serial No. 5,312

Term of patent 14 years

(Cl. D64—11)

To all whom it may concern:

Be it known that we, George H. Kress and Carl W. Sundberg, citizens of the United States, residing respectively at Vestal, county of Broome, State of New York, and Detroit, county of Wayne, State of Michigan, have invented a new, original, and ornamental Design for a Key Punch, of which the following is a specification, reference being had to the accompanying drawing, forming part thereof.

Fig. 1 is a perspective view of a key punch showing our new design.

Fig. 2 is a front elevation.

Fig. 3 is a side elevation.

The back of the key punch is plain.

We claim:

The ornamental design for a key punch, as shown and described.

GEORGE H. KRESS.
CARL W. SUNDBERG.
